Attorney

UNITED STATES PATENT OFFICE.

HARRY J. WALLACE, OF CLARKSBURG, WEST VIRGINIA.

DRAIN BOARD.

1,405,881.

Specification of Letters Patent. Patented Feb. 7, 1922.

Application filed March 16, 1921. Serial No. 452,737.

To all whom it may concern:

Be it known that HARRY J. WALLACE, a citizen of the United States, residing at Clarksburg, in the county of Harrison and

5 State of West Virginia, has invented certain new and useful Improvements in Drain Boards, of which the following is a specification.

This invention relates to new and useful 10 improvements in drain boards for sinks, and the primary object of the invention is to provide a device of this character which may be quickly and readily applied to any sink now in use or removed when desired.

15 It is a further object of my invention to provide such a device as may be purchased at a very low cost, one which can easily be applied to a sink not provided with a drain board and one which will enable the user to 20 remove the same at will, affording it in compact form to be placed out of sight when desired.

25 A further object of the invention resides in providing a drain board which when applied will be equally as firm and substantial in use and appearance as those permanently applied to the sink.

Still another object resides in providing 30 a device which is simple and durable in construction, inexpensive to manufacture and one which will be very efficient and useful in operation.

With these and other objects in view my 35 invention consists in the novel features of construction, combination and arrangement of parts as will be hereinafter referred to and more particularly pointed out in the specification and claims.

In the accompanying drawing—

40 Figure 1 is a side elevation of the drain board showing it applied to a sink which is in section,

Fig. 2 is a bottom plan view showing the parts in outspread position, and

45 Fig. 3 is a perspective view of the bracket or shoe and bolt.

In describing the invention I shall refer to the drawings in which similar reference characters designate corresponding parts 50 throughout the several views, and in which 1 designates a kitchen sink of the usual or

any preferred type, the sides and ends of which are beaded at their upper edges as shown at 2, as in the usual construction of sinks.

55

My invention includes a board of any preferred shape and size, to the under face of which adjacent one end is removably secured a pair of holders 4 which are arcuately designed and project slightly beyond one 60 end edge of the board. These holders are adapted to rest upon the beaded edge of the sink and hinged secured to the under face of the board 3 adjacent the opposite end is a leg or brace 5. This leg or brace is of a 65 length to permit of the free end abutting and resting against the side or end wall of the sink proper, and secured to the under face of the board 3 about midway of its ends is a U-shaped adjusting shoe or bracket 70 6. The leg or brace 5 is designed to project through this shoe or bracket 6 and a bolt 7 which projects through the aligning openings 8 in the arms of this bracket is adapted to receive the leg or brace 5 thereon when 75 the device is set up for use.

Thus the drain board is gripped against the beaded edge of the sink by the holders 4 and held in position by the leg or brace 5 which abuts the side or end wall of the sink 80 and rests upon the bolt 7 extended through the arms of the bracket or shoe 6.

From the foregoing description of the 85 construction of my improved invention, the operation thereof will be understood, and it will be seen that I have provided a simple, inexpensive and efficient means for carrying out the objects of the invention.

While I have particularly described the 90 elements best adapted to perform the function set forth, it is obvious that various changes in form, proportion, and in the minor details of construction may be resorted to without departing from the spirit or sacrificing any of the principles of the 95 invention.

Having thus described my invention, what I claim is:—

1. In combination with a sink, of a board, arcuate holders thereon engaging the edge of 100 one wall of the sink, a pivoted brace carried at the opposite end of the board and adapted

to engage at its free end the wall of said sink, and adjustable means suspended from said board to support said brace.

2. In combination with a sink, of a board, arcuate holders carried at one end of said board and engaging the upper edge of one wall of said sink, a brace hingedly carried at the opposite end of said board and adapt-

ed to have its free end abut the wall of said sink, a U-shaped bracket suspended from said board and receiving said brace there-through, and a bolt adjustably supported between the arms of said bracket to support said brace thereon.

In testimony whereof I affix my signature. 15
HARRY J. WALLACE.
